(57) **CLAIM**

The ornamental design for a bottle, as shown and described.

DESCRIPTION

FIG. 1 is a top perspective view of an embodiment of a bottle showing our new design;

FIG. 2 is a bottom perspective view thereof;

FIG. 3 is a front elevation view thereof;

FIG. 4 is a left side elevation view thereof, wherein a right side elevation view is a mirror of FIG. 4;

FIG. 5 is a top plan view thereof;

FIG. 6 is a bottom plan view thereof;

FIG. 7 is a rear elevation view thereof; and

FIG. 8 is a cross-section taken along the line 8-8 of FIG. 4;

FIG. 9 is a cross-section taken along the line 9-9 of FIG. 3; FIG. 10 is a cross-section taken along the line 10-10 of FIG. 3;

FIG. 11 is a perspective view of a cross-section taken along the line 11-11 of FIG. 4; and, FIG. 12 is another perspective view of a cross-section taken along the line 12-12 of FIG. 4.

The broken lines shown in the figures form no part of the claimed design.

1 Claim, 11 Drawing Sheets
